UNITED STATES PATENT OFFICE

ALEX R. YESCHICK, OF BROWNTON, MINNESOTA.

SWITCH

Application filed November 29, 1932. Serial No. 644,893.

My invention relates generally to switches, and particularly to a new and novel form of snap switch, which can be embodied in different electrical organizations, and substituted for wall and panel switches.

It is an important object of my invention to provide a positive acting switch of the type described having only one main moving part, which is movable as a whole for making and 10 breaking the circuit connected thereto.

It is also an important object of my invention to incorporate in the said moving part so as to be carried thereby, means for snapping open, that is, quickly disconnecting from 15 electrical engagement with a stationary contact of the switch, the movable member thereof.

It is also an important object of my invention to provide means incorporated in the 20 means for producing the snap action, for temporarily bridging the space between the movable member and the stationary contact so as to enable the movable member to separate from the stationary contact member 25 with but little arcing.

Other objects and advantages of my invention will be apparent from a reading of the following description in connection with the drawings, wherein for purposes of illustration I have shown a preferred embodiment of 30 the invention.

In the drawings:—

Figure 1 is a front view of the embodiment of the invention utilized as a wall 35 switch.

Figure 2 is a vertical transverse sectional view through Figure 1, taken approximately upon the line 2—2.

Figure 3 is a vertical transverse sectional 40 view taken through the switch structure.

Figure 4 is a horizontal transverse sectional view taken approximately on the line 4—4 of Figure 3.

Figure 5 is a vertical transverse sectional 45 view through the movable member.

Figure 6 is a vertical transverse sectional view taken approximately on the line 6—6 of Figure 3.

Figure 7 is a perspective view of the main 50 portion of the movable member.

Figure 8 is a perspective view of the mask for closing the opening in the base of the switch.

Figure 9 is a front view of one of the sections of the switch body. 55

Figure 10 is a back view of the front section of the switch body.

Figure 11 is a front view of the section shown in Figure 10.

Figure 12 is a perspective view of the switch 60 base.

Figure 13 is an elevational view of the stationary contact member.

Figure 14 is a transverse sectional view through Figure 13, taken approximately on 65 the line 14—14.

Figure 15 is a perspective view of the stationary contact engaging head of the movable member.

Referring in detail to the drawings, where- 70 in like numerals refer to like parts throughout the same, the letter A refers generally to the body of the switch which comprises the front section 1 and the rear section 2, which are made of suitable dielectric material 75 either cast or molded or otherwise formed to the shape shown.

The front section 1 shown in detail in Figures 10 and 11, comprises a vertically elongated block of generally rectangular form 80 which has formed in its ends notches 1a for receiving the heads or ends of bolts which may be passed through the base to be described. A longitudinal opening 3 is placed centrally intermediate the ends of the block. 85 In the back or reverse side of the block there is provided a recess 3a which is semi-circular in cross section. At either end of the recess 3a is a flattened portion 4, 5. Openings 6, 7 are made through the blocks on opposite 90 sides of the recess 3a to receive fastening means to be described.

The body section 2 is similar in forma- 95 tion to the body section 1 except for the provision of lugs 8 and 9 which are formed on one side of the block at the ends thereof as shown in Figure 9.

The body sections 1 and 2 are secured together in superposed relation with the recesses thereof 3a and 3b opposed, and the 100

front face of the section 1 abutted with the rear face of the base plate 10 which is shown in Figure 12. This comprises a suitable metallic or other rigid plate which has an elongation slightly greater than that of the body portion of the switch. A longitudinal opening 11 is provided intermediate the ends of the base plate for slidably accommodating the slidable mask 12 and the handle of the movable member B. On either side of the opening 11 in the base plate are openings corresponding in position to the openings 6 and 6a and 7 and 7a of the sections of the body A of the switch. In either end of the plate 13 is a transversely elongated opening 13 to receive securing means to be described.

For securing together the base plate 10, the front section 1 and the rear section 2 of the body of the switch, there are provided screws 14, 15 the heads of which are countersunk in the openings in the base plate and pass through the section 1 and are threaded into suitable threaded sleeves 16, 17 embedded in the section 2 as seen in Figure 4.

25 A suitable casing 18, in the form of a box having flanges 19 at its open side, may enclose the body of the switch in such a manner that the flanges 19 abut the rear side of the base plate 10. For mounting the switch 30 in a panel or wall construction a suitable opening is provided in the panel 20 so that the casing may be seated therein with its flange engaging and countersunk in the front face of the panel as shown in Figure 2. A 35 larger opening in the face plate 21 of the panel construction receives the base plate 10, and closing this latter opening is the switch plate 22 which may be of any desired design having centralized longitudinally spaced 40 openings to receive bolts or screws 23, 24 which pass through the transversely elongated openings 13, in the ends of the base plate 10.

45 Slidable in the chamber of cylindrical form constituted by the body sections 1 and 2 is the movable member generally designated B in the drawings. This comprises a tubular cylinder 25 of dielectric material which is of an exterior diameter to slide closely but easily 50 in the cylindrical chamber mentioned. As seen in Figure 3 the cylinder 25 is considerably shorter than the chamber, so that it may travel longitudinally therein. Extending from one side and integrally formed with the 55 cylinder 25 is a curved handle 26 which is of a size to slide in the opening 3 and fairly closely fit therein. It will be observed that the ends of the opening 3 are curved to conform with the curvature of the arm 26 as 60 shown in Figure 3. This permits a full bearing for the handle 26 to strike at the end of its travel in either direction.

65 For closing the opening 3 in all positions of the handle 26, I provide the mask 12 which has one half of a light color as indicated at 27

and the other half of a contrasting color as indicated at 28. This mask is disposed in the opening 11 of the base plate and slides in this opening and against the front face of the section 1 over the opening 3. The mask is provided with a central opening 29 to receive the handle therethrough, and the handle is provided with an enlarged head 30 which provides shoulders for confining the mask in position. The enlarged head 30 resembles the switch knob of an ordinary wall switch as seen in Figure 1. When the switch is in the "off" position the contrasting color portion 28 shows in the opening 31 in the switch plate 22 in which the handle works, whereas in the "on" position the lighter colored portion 27 appears in the opening 31, thereby positively indicating the position of the switch.

The means for producing a snap separation of the electrical contact member of the movable member from the stationary contact means of the switch, comprises the hollow tubular slide 32, which is open at its lower end. The slide 32 is of suitable conductive material. It is normally drawn downwardly 90 in the dielectric cylinder 25 by a spring 33 which is connected to the lower end of the slide 32 by a cross bar 34 and connected to the lower end of the dielectric cylinder 25 by another cross bar 35. As seen, a suitable 95 conductor 36 may be led through the lower open end of the dielectric cylinder 25 and connected to the cross bar 34 of the slide for introducing one side of the circuit into the switch.

The upper end of the tubular conductor slide 32 is pinched together and reduced in diameter as indicated at 37 in such a manner that divergent lips 38 and 39 are produced, between which lips is held a fiber or other 105 insulating material contact head 40 the precise form of which is shown in Figure 15.

The dielectric head 40 is generally arrow-shaped and is provided at opposite sides with plane angular related faces 41 and 42. The reduced shank portion 43 of the head 40 is provided in one side with a longitudinal opening 44 to receive the arc reducing member to be described.

115 The head 40 is adapted to meet and engage between and separate lips 45, 46 of the stationary spring contact generally designated 47, so as to pass between the lips 45, 46 and seat behind them as shown in Figure 5, in which position the lips of the stationary contact member electrically engage with the lips 38 and 39 on the adjacent end of the tubular slide 32 whereby full electrical contact is established and a structural as well as frictional engagement of the movable contact member with the stationary contact members brought about.

120 The stationary contact 47 is seen in Figures 13 and 14 comprises the plate portion 48 having the converging arms 49 and 50. Extended 125

ing laterally from one of the arms is an extension 51 which, as seen in Figure 9 extends to and is secured on the lug 8 of the body section 2, while the main portion of the stationary 5 contact member is seated upon the flattened portion 4a in that end of the recessed side of the body section 2, in position to be engaged by the dielectric head 40 of the movable member as it is moved upwardly into closed position. Resting upon the other flattened portion 5a at the opposite end of the recess 3b is a suitably formed L-shaped conductor 52 which has a lateral portion similar to the portion 51 extended to the lug 9. Suitable 10 screws or binding posts 53, 54 are threaded into the lugs in contact with the conductors 51 and 52 for connecting the circuit conductors 55 and 56 as seen in Figure 2.

In the forward leg 49 of the stationary 20 contact member 47 is an opening 57 formed by punching out a portion thereof and turning up the resultant tab as indicated at 58.

Pivottally supported on a pin 59 in the recess 44 in the dielectric head 40 is a spring 25 coil 60 of a spring member generally designated 61. This comprises the coil 60 the lower arm 62 which is extended within the tubular slide 32 and engages against one side thereof as seen in Figure 5, and the other 30 arm 63 which extends upwardly through the upper part of the recess 44 in the head and extends outwardly from the head. The arms 62 and 63 are so related to the coil 60 that the arm 63 is normally outwardly sprung 35 pressed. This arrangement of the arc reducing member is made so that as the head 40 approaches a position between the lips 45, 46 of the stationary contact, the upwardly directed end of the arm 63 will engage the 40 lip 45 and by reason of the upward movement of the slide 32 and the angular position of the lip 45, will be forced radially inwardly against the head 40 until the head 40 has passed beyond the lips 45, 46 into the position 45 shown in Figure 5, when, the arm 63 will spring radially outwardly into the opening 57 in the arm 49 of the stationary contact member. This results in a very positive contact and securely holds the head 40 engaged with the stationary contact element. The arc reducing function of the spring member 60 commences as the head 40 approaches the stationary contact. It will be observed that the arm 63 extends radially 55 outwardly of the head 40 so that it comes first into contact with the stationary contact element and maintains a arc reducing contact until the head 40 is properly seated so that the stationary contact element engages the tubular slide. When the tubular member 32 is separated from electrical contact with the stationary contact member, the arc reducing member 61 remains in contact with the arm 49 of the stationary contact 60 longer than any portion of the tubular slide

32, thereby practically preventing arcing which would otherwise occur between the arms of the stationary contact and the lip portions 38, 39 of the end of the tubular conductor. Owing to the spring character 70 of the arm 63, it will snap away from the arm 49 of the stationary contact element as soon as the slide 32 has been moved sufficiently away from the stationary contact element to separate the head 40 therefrom. This snap 75 action is aided by the spring 33 which draws the tubular conductor 32 downwardly into the open or off position. There is also a certain amount of snap action as the movable member separates from the stationary contact, due to the formation of the parts already described.

It will be observed that the movement of the tubular slide 32 is limited by means of a transverse member 65 which is arranged 80 diametrically in the dielectric cylinder 25 and passes through openings 66 in the opposite sides of the tubular slide 32. This construction is clearly seen in Figures 5 and 6.

It will be obvious that due to the relatively 85 heavy construction of the operative parts, that a heavy load current may be controlled thereby. By reason of this, expensive switch constructions now provided for controlling heavy load currents may be supplanted at 90 a much lower cost, and the necessity for a distant control switch for controlling the main switch from a convenient place may also be dispensed with, since the entire circuit control means for a heavy load circuit 100 may be located as a unit at any convenient place, such as in a wall or panel or in any desirable place.

Though I have shown and described herein a preferred embodiment of the invention, it is to be definitely understood that I do not desire to limit the application of the invention thereto, and any change or changes may be made in material and structure and arrangement of parts, within the spirit of the invention and the scope of the subjoined claims.

What is claimed is:—

1. A switch of the class described comprising a casing, a stationary contact member in one end of the casing comprising a pair of spring fingers having their major portions convergently arranged with their terminals flaring, a cylinder of non-conducting material in the casing, a handle connected therewith, an inner cylinder slidably arranged in the first-mentioned cylinder and formed of conductive material with its outer end reduced and terminating in a flaring part, a head of non-conductive material placed in the flaring portion with its outer part projecting therefrom and of wedge shape, and spring means for connecting the two cylinders together. 115 120 125 130

2. A switch of the class described comprising a casing, a stationary contact member in one end of the casing comprising a pair of spring fingers having their major portions convergently arranged with their terminals flaring, a cylinder of non-conducting material in the casing, a handle connected therewith, an inner cylinder slidably arranged in the first-mentioned cylinder and formed of conductive material with its outer end reduced and terminating in a flaring part, a head of non-conductive material placed in the flaring portion with its outer part projecting therefrom and of wedge shape, spring means for connecting the two cylinders together, a spring tongue carried by the head and passing through an opening in the flaring part of the inner cylinder, and the stationary contact having an opening in one finger thereof for receiving the tongue, a part of the metal left by the opening being bent outwardly to engage the tongue.

3. A switch of the class described comprising a casing, a stationary contact at one end of the casing composed of a pair of spring fingers, an outer cylinder slidably arranged in the casing, the inner cylinder having limited sliding movement in the outer cylinder, the outer end of the inner cylinder being of substantially dome-shaped and terminating in a flaring portion, a head of non-conducting material passing through the flaring portion and shaped to conform therewith with the outer end of the head of wedge shape, a spring member carried by the head and having a tongue forming portion passing through a part of the flaring portion of the inner cylinder and one of the fingers of the stationary contact having an opening therein for receiving the tongue with the metal left by the opening pressed outwardly, a spring connecting the inner cylinder with the outer cylinder and a handle connected with the

outer cylinder and passing through a slot in the casing.

4. A device of the class described comprising a casing formed of non-conductive material and having a slot therein, a movable switch member located in the casing and composed of inner and outer cylinders, a stationary contact for one end of the casing and composed of spring fingers, the inner cylinder having its outer end reduced and ending in a flaring portion engaging the spring fingers, yieldable means connecting the two cylinders together, a handle on the outer cylinder passing through the slot in the casing, a plate having one portion of a different color than the other portion with an opening in the plate through which the handle passes, a second plate in which the first-named plate is slidably arranged, and a cover plate connected with the second plate and having a slot therein through which the handle passes.

5. A switch of the class described comprising a casing, a substantially U-shaped spring member at one end of the casing forming a stationary contact, a member slidably arranged in the casing and having one end reduced and adapted to enter the space between the limbs of the stationary contact, said member forming a movable contact, a wedge-shaped part carried by the reduced end of said member for moving the limbs of the stationary contact apart, said wedge part being formed of non-conducting material, a spring tongue carried by said wedge shaped part and passing through an opening in the reduced part and one limb of the stationary contact having an opening therein for receiving the tongue, a part of the metal left by the opening being bent outwardly to engage the tongue and a handle connected to the sliding member.

In testimony whereof I affix my signature.

ALEX R. YESCHICK.
